Attorney.

UNITED STATES PATENT OFFICE.

JAMES A. CREAGER, OF OKLAUNION, TEXAS.

DISK PLOW.

SPECIFICATION forming part of Letters Patent No. 731,436, dated June 23, 1903.

Application filed March 24, 1903. Serial No. 149,264. (No model.)

To all whom it may concern:

Be it known that I, JAMES A. CREAGER, a citizen of the United States, residing at Oklaunion, Texas, have invented certain new and useful Improvements in Disk Plows, of which the following is a specification.

This invention relates to plows provided with a plurality of rotary blades or disks for the purpose of plowing up land; and the object is to simplify the construction of plows of this class and to make the same less dangerous to the operator and to make plows stronger and more durable and efficient.

Other objects and advantages will be fully explained in the following description, and the invention will be more particularly pointed out in the claims.

Reference is had to the accompanying drawings, which form a part of this specification.

Figure 1 is a rear elevation of the plow. Fig. 2 is a plan view of the plow in position for plowing, the tongue being broken away. Fig. 3 is a sectional view of the gang-board, showing one of the hangers for the gang-shaft attached thereto, thus illustrating the manner of attaching the hangers to the gang-board. Fig. 4 is a cross-section of the gang-board along the line xx of Figs. 1 and 2, illustrating the manner of attaching the guide-wheels.

Similar characters of reference are used to indicate the same parts throughout the several views.

My invention is provided with a tongue 1, mounted on the gang-board 2 and secured thereon by a suitable bolt 4 and is further secured and made rigid by the bar 3, which serves as a brace. A hound 5 is attached to the tongue by suitable bolts and to the gang-board 2 by the bolt 6, the hound being twisted one-quarter around. The gang-board 7 is attached to the gang-board 2 by means of bolts 8 and 9, the end of the gang-board 2 being extended far enough on the side of the tongue next to the gang-board 7 for this purpose. The hound 10 is attached to the tongue 1 and twisted one-quarter around and attached to the gang-board 7 and secured thereto by a bolt 11. The hound 10 and the bar 3 add strength and firmness to the gang-board 7. The gang-boards are preferably made of slab-steel.

The board 7 is made adjustable relative to the other parts of the machine for the purpose of regulating the depth of the plows or causing the plows to run on top of the ground. The manner of adjusting this board is shown in Fig. 2. The bolt 9 may be called the "pivot-bolt." A slightly-curved slot 12 is made in the board 7 for the bolt 8, and a curved slot 13 is made in the board 7 for the bolt 11. When the board is to be adjusted, the nuts on bolts 11 and 8 are loosened. The board 7 is then turned backward or forward, as may be desired. In the position shown in Fig. 2 the plows are set to run to their greatest depth. If the plowing is to be shallower, the bolts 8 and 11 are loosened and the board 7 swung backward on the bolt 9 as a pivot to desired position. If the plows are to be made to run on top of the ground, bolts are loosened and the board 7 swung backward until this board comes in line with the board 2.

The plows are mounted on one side of the machine, and the guides are mounted on the other side of the machine, and the gangs can be set at different angles and made rigid with each other at various adjustments by the elements described in the previous paragraph. The plows 14 are mounted on the gang-board 7 by means of a gang-rod or gang-shaft 15, which is attached to the gang-board 7 by means of hangers 16 and 17, the hanger 17 being mounted on the outside of the outside plow. The hangers 16 and 17 are provided with bearings 18, bolted thereto, for the shaft 15. The hangers are secured to the gang-board 7 by means of bolts 19 and 20. The plows are circular and concave in shape, they being concave on the side on which the dirt is to be thrown.

The guides 21 are mounted on the opposite side of the plow from the blades 14 and run on top of the ground. The guides 21 are secured to the gang-board 2 by means of the gang-shaft 22, which is mounted in hangers 23 and 24. The hangers 23 and 24 are attached to the gang-board 2 in the same manner as the hangers 16 and 17 are attached to the gang-board 7, and these hangers 23 and 24 are provided with bearings 25 for the shaft 22.

In addition to the means for regulating the

depth which the blades 14 are to run already described I have provided gage-wheels 26, one on each side of the group of blades. These gage-wheels may be mounted on the gang-board 7 in any suitable manner. I show these wheels mounted in bifurcated hangers 27. The ends of the slabs forming the gang-board may be bent down to form the depending flanges 28, and brackets 29 are bolted to the under side of the gang-board 7. (See upper right side of Fig. 1, a portion of the side flange being broken away.) The hangers 27 are provided with a number of bolt-holes, so that these hangers may be attached to the flanges 28 and brackets 29 at different adjustments.

It will be noticed that the gang-shafts of the cutting-blades 14 and of the guides 21 are not connected. It has been found by actual work that the plow does better service with these gang-shafts running independent of each other. The cutting-blades are more easily adjusted and the blades are more free to run. The gang-shafts are held rigidly with the gang-boards by the hangers. It will be noticed that gang-boards have depending flanges 30. These flanges brace and strengthen the hangers. The gang-board 7 is held securely in place by the hound 10, the gang-board 2, and the brace 3.

I have provided scrapers 31 for blades 14. These scrapers are mounted on a shaft 32, which is mounted in hangers 33, which are attached to the gang-board 7 by bolts 19 and 20, as shown in Fig. 3.

Having fully described my invention, what I claim as new, and desire to secure by Letters Patent, is—

1. A disk plow comprising a gang-board 40 for guides, a blade gang-board attached to said guide gang-board and adapted to be attached thereto at different adjustments, a tongue attached to said guide gang-board, hounds attached to said tongue and to said gang-boards, a brace for said hounds and for said gang-boards, gang-shafts attached to each of said gang-boards and operating independently of each other, and suitable guides and blades mounted on said shafts.

2. A disk plow comprising a guide gang-board having guides attached thereto, a blade gang-board adjustably attached to said guide gang-board, gang-shafts, hangers for said shafts attached to said gang-boards, said 55 gang-boards having depending flanges brac-

ing said hangers, and blades mounted on the gang-shaft for said blade gang-board.

3. A disk plow comprising a guide gang-board, a blade gang-board adjustably and rigidly attached to said guide gang-board, a tongue provided with hounds bracing said gang-boards, gang-shafts, hangers for said gang-shafts attached to said gang-boards, said gang-shafts being mounted and operating independently of each other, and suitable guides and blades mounted on said gang-shafts.

4. A disk plow comprising a guide gang-board, a blade gang-board, means for adjustably attaching said blade gang-board to said guide gang-board consisting of a pivot-bolt and a bolt for attaching said gang-boards at different adjustments, said blade gang-board having a curved slot for the last-named bolt, gang-shafts for each of said gang-boards operating independently of each other, hangers for said shafts, and guides and blades suitably mounted on said shafts.

5. A disk plow comprising a guide gang-board, a blade gang-board, a tongue and hounds bracing said gang-boards, means for adjustably attaching said blade gang-board to said guide gang-board and to one of said hounds consisting of a pivot-bolt and an adjustable bolt, said blade gang-board having a curved slot for said last-named bolt, a bolt securing one of said hounds to said blade gang-board, said gang-board having a curved slot for said last-named bolt, means for attaching guides to said guide gang-board, and means for attaching blades to said blade gang-board.

6. In a disk plow the combination of a gang of disks set at an angle to plow the ground, a gang of guide-blades, and means for connecting said gangs rigidly together.

7. In a disk plow the combination of a gang of disks angled to plow the ground, a gang of guide-blades, and means for connecting said gangs rigidly together, said gangs being adapted to be set at different angles to each other.

In testimony whereof I set my hand, in the presence of two witnesses, this 6th day of February, 1903.

JAMES A. CREAGER.
